No. 15,031

May 27, 1884

UNITED STATES PATENT OFFICE.

LOUISE TULLY, OF NEW YORK, N. Y., ASSIGNOR TO THE BUTTERICK PUBLISHING COMPANY, (LIMITED,) OF SAME PLACE.

DESIGN FOR A LADY'S BASQUE.

SPECIFICATION forming part of Design No. 15,031, dated May 27, 1884.

Application filed March 27, 1884. Term of patent 3½ years.

To all whom it may concern:

Be it known that I, LOUISE TULLY, of the city, county, and State of New York, have invented and produced a new and original Design for a Pattern of a Lady's Basque, (numbered 9,154;) and I do hereby declare that the engraved prints accompanying this specification convey to any one accustomed to using paper patterns a clear understanding of how a garment made up by the pattern will appear.

The design shows closely-fitted fronts with buttons down the center, a closely-fitted back, coat-sleeves, and a standing collar. It out-

lines a short oval back of each front edge, a deeper, broader oval at each side, and four 15 deep oval tabs at the back.

What I claim as my invention, and desire to secure by Letters Patent, is—

The design for a lady's basque, as shown in the engraved prints accompanying this specification.

LOUISE TULLY.
